UNITED STATES PATENT OFFICE.

ARTHUR C. WOOD, OF MANSFIELD, OHIO, ASSIGNOR TO THE OHIO BRASS COMPANY, OF MANSFIELD, OHIO, A CORPORATION OF NEW JERSEY.

CONDUCTOR SUPPORT.

Application filed December 6, 1922. Serial No. 605,266.

To all whom it may concern:

Be it known that I, ARTHUR C. Wood, a citizen of the United States of America, residing at Mansfield, in the county of Richland and State of Ohio, have invented certain new and useful Improvements in Conductor Supports, of which the following is a specification.

My invention relates to supports for conductors and particularly that class of support by means of which the conductor may be gripped and secured to a hanger.

The object of my invention is to produce a cheap, simple, efficient device which can be easily secured to the conductor and hanger and easily removed therefrom.

My invention resides in the new and novel construction, arrangement and combination of the various elements more fully hereinafter described and shown in the drawings.

In the drawings:

Fig. 1 is a view in elevation of a device embodying my invention secured to a conductor.

Fig. 2 is an end view in elevation of Fig. 1.

Fig. 3 is a transverse sectional view of Fig. 1 on the line 3—3.

Fig. 4 is a longitudinal sectional view taken on the line 4—4 of Fig. 2.

Fig. 5 is a transverse sectional view of Fig. 1 with the exception that the device is shown secured to a hanger H and the jaws opened up to receive a conductor C.

Fig. 6 is a horizontal sectional view taken on the line 6—6 of Fig. 3.

In the preferred form of device embodying my invention I employ a supporting member 1 provided with a threaded recess 2 by means of which the device may be secured to the stud of a hanger H. At the lower end of the member 1 is a horizontal projecting flange 3. Rotatably mounted upon the supporting member 1 and held against lateral movement in one direction by the flange 3 is a member 4 provided with polygonal faces F arranged for the application of a wrench or other means for operating the rotatable member 4. Engaging with and supported by the member 4 is a connecting member 5 having a threaded engagement 6 with the member 4. The connecting member 5 is recessed and within the recess 55 are mounted a pair of jaws 7 provided at

their lower ends with lips 8 to engage the conductor C. The distance A between the adjacent faces of the jaws 7—7 is sufficiently great to permit the jaws to be entered through the lower opening into the recess 9 of the member 5.

To retain the jaws within the recess 9 I provide two lugs 10 projecting from the lower end of the member 1 and spaced apart and which provide a transverse channel 11 therebetween. The lugs 10 projecting within the space between the upper ends of the jaws engage therewith and prevent the jaws moving together a sufficient amount to fall out of the member 5 as the jaws are not capable of moving toward each other at the upper end a sufficient distance to pass through the lower opening in the member 5. Projecting inwardly from diametrically opposite points at the upper end of each jaw 7 is a lug 12 positioned within the channel 11 and this arrangement interlocks the supporting member 1 and the jaws against relative rotation. This permits the clamp to be secured to the hanger by gripping the jaws with the hand or a wrench and rotating the same, which in turn rotates the member 1 into engagement with the hanger H. Projecting inwardly and at diametrically opposite points of the member 5, and within the recess are narrow lugs 13 which engage with the adjacent inner faces of the jaws at their upper end and prevent relative rotation of the jaws with respect to the connecting member 5.

This construction permits the jaws and connecting member to not only pivot relatively to each other about the point of engagement 14, but to also have a sliding engagement at this point relative to each other. The upper and outer edges 15 of the jaws 7 are arranged to engage with the flange 3.

To install my device upon a hanger and conductor, the device is first secured to a hanger stud H by gripping the jaws by means of the hands and rotating the member 1 into position upon the hanger stud. This is possible through the fact that the jaws and member 1 are interlocked as described or the member 5 may be rotated and the member 1 secured into position upon the hanger stud for the reason that the member 5 is interlocked with the jaws and the jaws in turn interlocked with the member 1. If the jaws are not sufficiently open

to receive the conductor the member 4 is rotated in the proper direction to permit the member 5 to move downward. This will permit the jaws to slide apart as shown in Fig. 5. After introducing the conductor in position between the lips 8-8 the member 4 is rotated in the opposite direction thereby drawing the member 5 upward and the jaws simultaneously therewith, and this movement after it is completed will force the jaws to pivot and also slide about their point of engagement 14 with the member 5 due to the engagement of the jaws with the flange 3 and the tapered face 16 on the exterior upper end of each jaw. This rotation of the member 4 can be made by means of the hand until the lips 8 engage the conductor after which a wrench applied to the faces F of the member 4 will bring the jaws into further secure engagement with the conductor.

It will be evident to one skilled in the art that there are modifications which may be made in the construction herein disclosed, but which will fall within the scope of my invention, therefore, I do not wish to be limited other than by my claims.

Claims:

1. A conductor clamp comprising in combination a pair of jaws to grip a conductor, a supporting member to secure the clamp to a hanger, a rotatable member mounted on the supporting member, means on the supporting member interposed between and engaging the rotatable member and jaws, a connecting member provided with means to support the jaws in pivotal and slidable relation, means on the connecting member engaging with means on the rotatable member to move the jaws and connecting member relative to the supporting member when the rotatable member is rotated and cause the jaws to move into engagement with the conductor.

2. A conductor clamp comprising in combination a pair of jaws to grip a conductor, a supporting member to secure the clamp to a hanger, a rotatable member mounted on and supported by the supporting member, a connecting member provided with means to support the jaws in pivotal relation, and means on the connecting member coacting with means on the rotatable member to move the connecting member relative to the jaws and force the jaws into engagement with the conductors when the rotatable member is rotated.

3. A conductor clamp comprising in combination a pair of jaws to grip a conductor, a supporting member to secure the clamp to a hanger, a rotatable member supported by the supporting member, a connecting member provided with means to support the jaws in pivotal and slidable relation, a tapering surface on each jaw engaging the last said

means, and means on the connecting member engaging with means on the rotatable member to move the connecting member relative to the jaws and force the jaws into engagement with the conductor.

4. A conductor clamp comprising in combination a pair of jaws to grip a conductor, a supporting member to secure the clamp to a hanger, a rotatable member mounted on and supported by the supporting member, a connecting member provided with means to support the jaws in pivotal and slidable relation, and means on the connecting member coacting with means on the rotatable member to move the jaws into engagement with the supporting member and the conductor when the rotatable member is rotated.

5. A conductor clamp comprising in combination a pair of jaws to grip a conductor, a supporting member to secure the clamp to a hanger, a two-part means to suspend the jaws from the supporting member in pivotal and slidable relation thereto to force the jaws into engagement with the supporting member and to slide and pivot them about their engagement with the last said means and into engagement with the conductor.

6. A conductor clamp comprising in combination a pair of jaws to grip a conductor, a supporting member to secure the clamp to a hanger, means to suspend the jaws from the supporting member in pivotal and slidable relation thereto, said means comprising two relative rotatable coacting elements movable towards each other when rotated to move the jaws into engagement with the supporting member and the conductor.

7. A conductor clamp comprising in combination a pair of jaws to grip a conductor, a supporting member to secure the clamp to a hanger, means to suspend the jaws from the supporting member, comprising two relative rotatable engaging elements movable towards each other, a tapering surface on each jaw engaging with one of the said elements in slidable relation thereto, to force the jaws into engagement with the supporting member and conductor when the other element is rotated.

8. A conductor clamp comprising in combination a supporting member, a rotatable member supported on the supporting member, a connecting element having a rotatable engagement with the rotatable member and a pair of jaws interlocked with the supporting member and the connecting element against relative rotation and having a pivotal and slidable engagement with the connecting element and means whereby the rotatable member may be rotated and the jaws forced into engagement with the supporting member and conductor.

9. A conductor clamp comprising in combination a supporting member, a member

supported on the supporting member, a connecting element having a rotatable engagement with the member and a pair of jaws interlocked with the supporting member 5 against relative rotation and having a pivotal and slid able engagement with the connecting element and means whereby the jaws may be forced into engagement with the supporting member and conductor when the 10 member and connecting element are rotated relative to each other.

10. A conductor clamp comprising in combination a supporting member, a pair of jaws to engage a conductor, a connecting member to engage and support the jaws in movable relation thereto and means rotatably mounted on the supporting member and engaging and supporting the connecting member to force the connecting member into 20 engagement with the jaws and the jaws into engagement with the conductor when the said means is rotated.

11. A conductor clamp comprising in combination a pair of movably mounted jaws to grip a conductor, a supporting member to secure the clamp to a hanger and interlock with the jaws against relative rotation, connecting means to suspend the jaws from the supporting member and rotatable means 30 coacting with the supporting member and the connecting means to force the jaws into engagement with the conductor.

12. A conductor clamp comprising in combination a pair of movably mounted jaws to 35 grip a conductor, a supporting member to

secure the clamp to a hanger, connecting means to suspend the jaws from the supporting member, means preventing relative rotation of the jaws and connecting means, and rotatable means coacting with the supporting member and the connecting means to force the jaws into engagement with the conductor. 40

13. A conductor clamp comprising in combination a supporting member, a pair of 45 movable jaws to engage and grip a conductor, a two part means connecting the jaws to the supporting member, one part of said means engaging the jaws in movable relation thereto and the other part of said means 50 engaging the supporting member, coacting threads on each part of said means to move the jaws into engagement with the conductor when one of the parts of said means is rotated. 55

14. A conductor clamp comprising in combination a pair of movably mounted jaws to grip a conductor, a supporting member to secure the jaws to a hanger and interlock with the jaws against relative rotation, connecting means to suspend the jaws from the supporting member, means preventing the relative rotation of the jaws and connecting means and rotatable means coacting with the supporting member and the connecting means 60 to force the jaws into engagement with the conductor. 65

In testimony whereof I affix my signature.

ARTHUR C. WOOD.
